UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO PREVENT ROLLING OF BOBBINS.

Application filed February 29, 1924. Serial No. 696,039.

To all whom it may concern:

Be it known that I, WALTER H. WAKEFIELD, a citizen of the United States, residing at Worcester, in the county of Worcester and State of Massachusetts, have invented a new and useful Device to Prevent Rolling of Bobbins, of which the following is a specification.

This invention relates to weft replenishing mechanism for looms and more particularly to improved means for preventing the rotation of bobbins on their axes as they await transfer.

In my co-pending application, Serial No. 695,883 there is shown a pair of bobbin compartments between which is located an angularly movable wall under control of the weft replenishing mechanism and so disposed as to exert lateral pressure against the butts of the bobbins to force them against the fixed walls of the compartments. The purpose of this construction is to prevent rolling of the bobbins on their axes, as such rotation has been found to entangle the filling ends extending to the thread holder with the result that breaks are likely to occur at the time of transfer. In order to provide for inaccuracies in the diameters of the bobbins, the movable wall in said application is shown as being provided with a yielding covering which is deformable to engage the bobbins irrespective of their slight variations.

It is the principal object of my present invention to improve upon the bobbin engaging means by providing a separate yieldable device to frictionally engage each bobbin individually to prevent rotation thereof. Accordingly, I have provided a movable wall with a plurality of spring sections each positioned for engagement with a bobbin and all movable out of bobbin engaging position when the replenishing mechanism calls for a fresh bobbin to be inserted in the running shuttle so that the bobbins may be free to fall.

With this general object and others which will appear as the description proceeds, my invention resides in the combination and arrangement of parts hereinafter described and set forth in the claims.

In the accompanying drawings wherein I have shown one form of my invention, Fig. 1 is a side elevation of part of a re-

plenishing mechanism having my invention applied thereto as viewed from the center of the loom.

Fig. 2 is a vertical section taken on line 2—2 of Fig. 1,

Fig. 3 is an enlarged horizontal section taken on line 3—3 of Fig. 1,

Fig. 4 is a view similar to Fig. 3 but showing the movable wall in a different position, and

Fig. 5 is a detail view showing a portion of the movable wall.

Referring more particularly to Fig. 1 it will be seen that the replenishing mechanism comprises a frame 10 upon which is guided the vertical slides 11 and 12, the lower ends of which control cradles 13 and 14 for the purpose of advancing fresh bobbins to transfer position. The vertical slides are provided with upper and lower bosses 15 and 16, respectively, positioned for operation by an angularly and longitudinally movable rod 17 which is guided in bearings 18 and has fastened thereto a slide actuation finger 19 as indicated in Fig. 2.

A bearing block 20 held to the frame 10 by bolt and slot connections to afford horizontal adjustment has formed therein a bore 21 which receives the upper pin 22 of movable wall 23. The lower end of the wall is supported on a pin 24 which is fastened to the frame 10 and has an upbent end 25 which is received in a bore 26 formed in the wall. Extending from wall 23 at a point intermediate the ends thereof is an arm 27 to which is secured a cam plate 28 riveted or otherwise secured thereto.

Extending upwardly from the slides 11 and 12 are fingers 29 and 30, respectively, which are positioned for engagement with the cam plate 28 as the slides rise. A spring 31 extends between a fixed part of the replenishing mechanism and the plate 28 and serves normally to hold the wall in the position shown in Fig. 3. As the slides 11 and 12 are raised the corresponding fingers engage the cam plate to move the same to the position shown in Fig. 4 against the action of spring 31, thus releasing the bobbins so they may fall in the compartments. The latter thus far described is substantially as shown in Patent No. 1,030,740 and my aforesaid pending application.

My present invention relates more particu-

larly to the construction of the bobbin engaging portions of the wall 23 whereby each bobbin may be provided with an individual yielding friction member which is independent of the other members, each member engaging the corresponding bobbin and all the bobbins being restrained even though there may be slight differences in their diameters. Accordingly, as shown in Fig. 5, I have provided a pair of flexible strips 40 and 41 formed of spring steel or other suitable material. These strips are provided with transverse slits 42 and 43, respectively, so placed as to define bobbin engaging portions 44 and 45 respectively, the slits preferably lying intermediate the bobbins so that each bobbin will be provided with an engaging section. The slits do not extend entirely across the flexible strips, but terminate near one edge as indicated in Fig. 5. I do not wish to be limited to the length of the slits as the purpose of the present invention will be carried out if the bobbin engaging sections are independently movable. Rivets 46 or other means may be used to attach the strips 40 and 41 to the wall 23.

Under normal conditions the vertical slides are in the position indicated in Fig. 1 and the several bobbin engaging sections 44 and 45 are held in contact with their respective bobbins by spring 31. The bobbins are thus held against the fixed walls 47 and 48 respectively so that rotation on their axes is effectively prevented. Upon indication of weft exhaustion one or the other of the slides will be raised by finger 19 so that the cam plate 28 will be moved to the right as shown in Fig. 4, the result of which will be to move the wall sections away from the bobbins. The bobbin engaging sections 44 and 45 are thus moved to release the bobbins so that they may descend in the compartments formed between the movable walls and fixed walls 47 and 48. When transfer is called for the slide which was previously raised will be lowered and spring 31 will again restore the parts to the position shown in Fig. 3.

It will be seen from the foregoing that I have provided a very simple means under control of the replenishing mechanism for applying pressure against each bobbin so that although the various bobbins may of different diameters yet all will be restrained against rotation and the undesirable tangling of the ends which extend to the thread holder prevented. It is to be understood

that when the wall is moved to release the bobbins, all of the portions 44 and 45 will be in alignment so as not to interfere with the proper falling of the bobbins. It will be further noted that the mounting for the upper end of the movable wall permits adjustment thereof with respect to the fixed walls to provide for proper setting of said movable wall.

Having thus described my invention it will be apparent that changes and modifications may be made therein by those skilled in the art without departing from the spirit and scope of the invention and I do not wish to be limited to the details herein disclosed, but what I claim is:

1. In a replenishing mechanism for looms, a bobbin compartment having a fixed wall, and means under control of the replenishing mechanism to present a surface having a plurality of independently deformable portions to the bobbins to engage the latter and move the same against the fixed wall.

2. In a weft replenishing mechanism for looms, a bobbin compartment, and means providing a series of surfaces yieldable independently of each other to engage and resist rotation of the bobbins, all said surfaces being under control of the replenishing mechanism.

3. In a weft replenishing mechanism for looms, a bobbin compartment having a fixed wall, a movable wall under control of the replenishing mechanism, and means associated with the movable wall for presenting a plurality of separately yieldable surfaces to the bobbins.

4. In a weft replenishing mechanism for looms, a pair of bobbin compartments, a movable wall between said compartments, and means carried by the wall and under control of the replenishing mechanism to present an independently yielding friction surface to each bobbin of both compartments to prevent rotation of all of said bobbins.

5. In a weft replenishing mechanism for looms, a pair of bobbin compartments, a pivoted device common to both compartments, and means carried by the device to present a plurality of independently yieldable surfaces to the bobbins of both compartments.

In testimony whereof I have hereunto affixed my signature.

WALTER H. WAKEFIELD.
